UNITED STATES PATENT OFFICE

91,109

DESIGN FOR AN EMBROIDERED FABRIC SCARF OR SIMILAR ARTICLE

Moses F. Gantz, Yonkers, N. Y.

Application October 12, 1933. Serial No. 49,470

Term of patent 3½ years

To all whom it may concern:

Be it known that I, MOSES F. GANTZ, a citizen of the United States, residing at Yonkers, in the county Westchester and State of New York, have invented a new, original, and ornamental Design for an Embroidered Fabric Scarf or Similar Article, of which the following is a specification, reference being had to the accompanying drawing, forming part thereof.

The figure of the drawing is a plan view of approximately one-half of the embroidered fabric scarf or similar article showing my new design, the other half being a repetition thereof in reverse position.

I claim:

The ornamental design for an embroidered fabric scarf or similar article, as shown and described.

In testimony whereof, I hereunto affix my signature.

MOSES F. GANTZ.
